B. F. Lunk ATTORNEY

UNITED STATES PATENT OFFICE

FRED F. WELLMAN, OF WICHITA, KANSAS, ASSIGNOR TO THE WELLMAN CASING SPEAR COMPANY, A CORPORATION OF KANSAS

WELL-CASING PULLER

Application filed August 13, 1928. Serial No. 299,218.

This invention relates to casing pulling devices, sometimes designated a casing spear, a device used for lowering casing into the oil well and for jarring it loose preparatory to "pulling" it. Broadly, the invention contemplates a body member carrying a plurality of expanding and contracting slips or jaws, the latter being set into casing engaging position by overcoming the inertia of 5 a spring balanced weight, the mechanism being so constructed that the puller or spear can be caused to grip or release the casing as often as desired without the necessity of withdrawing the tool from the well and 10 since the slips or jaws are movable outwardly to an appreciable extent, the amplitude of movement is sufficient to serve for casings of different diameters, an important feature since the number of pullers or spears 15 required is reduced to a minimum.

The novelty of the invention will be clearly apparent by reference to the following description in connection with the accompanying drawings in which:

Fig. 1 is a vertical, longitudinal, sectional view through a well casing showing the tool in position to engage the interior wall of the casing.

Fig. 2 is a vertical, longitudinal, sectional view through the tool.

Fig. 3 is a fragmentary view showing part of the spring balanced weight, one of the slips and a link connecting them.

Fig. 4 is a sectional view on the line 4—4 of Figure 2 and

Fig. 5 is a sectional view on the line 5—5 of Fig. 2.

The tool is shown as comprising a sectional hollow body consisting of a lower member 1 and an upper member 2 screwed together or otherwise fastened together as indicated at 3. The lower member 1 has a rounded nose 4 relatively thick and provided with a recess 5. The upper member 2 is 40 tapered in an upward direction, being provided with a plurality of slip or jaw faces 6, 7 and 8, provided with dovetailed grooves 9, 10 and 11. Casing engaging slips or jaws 12, 13 and 14 ride on the tapered faces of 45 the upper member 2 and they carry dove-

tail keys 15, 16 and 17 to engage the respective grooves. The curvatures of the outer faces of the slips or jaws are approximately equal to the curvature of the inner face of the casing. The outer face of each jaw is 55 provided with teeth 18 as will be well understood. The upper member 2 is provided with a head 19 having a screw threaded projection 20 which engages a rod section 21 in an appropriate manner.

In screw threaded connection with the head 19 is a suspended rod 22, the lower end of which is screw threaded as at 23, supporting the weight 24 in the chamber 25, formed by the lower and upper members. 60 The screw threaded end 23 carries a nut 26 upon which one end of a spring 27, coiled about the rod 22, rests. The weight is seated upon the other end of the spring by means of the upper end 28 of the recess 29 in the weight 24 so that the weight floats on the spring. Each slip or jaw carries a stud or pin 30 which engages a link connected to the weight. There are three links shown. These are designated 31, 32 and 33 and their 65 lower ends are received in recesses in the upper end of the weight and are secured thereto by the pins 34.

Normally, the expansive force of the spring 27 holds the weight and jaws or slips 80 high enough so that the jaws or slips are in retracted position. If the tool is jerked upward slightly, the inertia weight will tend to remain stationary, in effect move downward, causing the slips or jaws to ride down and outwardly on the faces of the upper member 2 until the teeth of the slips or jaws come into contact with the interior face of the casing. A continued upward movement of the body member will cause 85 the slips or jaws to wedge between the body member and the casing so that the teeth of the slips or jaws will impinge upon the casing and effect positive engagement between the tool and the casing so that the casing 90 can be pulled. A downward movement of the body member will likewise effect a release of the casing. It will therefore be apparent that the puller or spear is quite sensitive both for engagement and release, that 95 100

it is positive in its action and that it can be rugged enough to meet all operating requirements.

The lock pin 31 prevents the members 1 and 2 from unscrewing. While I have shown the tool attached to a drill stem, it is obvious that it can be attached to casing; so I do not wish to be limited to the drill stem.

10 It will be observed that the upper ends of the slips or jaws 12, 13 and 14 are beveled downwardly and outwardly so as to provide outwardly inclined faces 35. This is for the purpose of preventing accumulation of mud or deposits upon the slips and to permit the mud to free itself when the tool is raised in the well. It will, also, be obvious that the nut 26 can be adjusted to vary the scale of the spring.

20 What I claim and desire to secure by Letters Patent is:—

1. A well casing pulling device comprising an elongated hollow member having tapered guide faces, casing engaging slips 25 slidable on said faces, a weight within the hollow member connected to said slips and a spring supporting said weight, the spring being collapsible when inertia of the weight is overcome to slide the slips into casing 30 engaging position.

2. A well casing pulling device comprising an elongated member having a tapered portion, casing engaging slips slidable on the tapered portion and a normally spring retracted slip actuating weight carried by the elongated member.

3. In a well casing pulling device of the character described, a body stock adapted for attachment at one end to the operating 40 rod or cable, a cylindrical tapered extension depending from the opposite end of said body stock, jaw members slidably arranged upon the outer face of said extension, a member depending from the center of the 45 extension, a weight member slidable upon said first mentioned member, means normally urging the weight member in an upward direction, and rigid connections between said weight member and said jaw members, all in the manner and for the 50 purpose described.

4. In a well casing pulling device of the character described, a body stock adapted for attachment at one end to the operating 55 rod or cable, a cylindrical tapered extension depending from the opposite end of said body stock, jaw members slidably arranged upon the outer face of said extension, a weight member slidable upon said pin, 60 spring means normally urging the weight member in an upward direction, and operative connections between the weight member and said sliding jaw members whereby to normally urge the jaw members 65 in an upward direction.

5. In a well casing pulling device of the character described, a body stock adapted for attachment at one end to the operating rod or cable, a cylindrical tapered extension depending from the opposite end of said body stock, jaw members slidably arranged upon the outer face of said extension, an elongated pin depending from the center of said extension, a weight member slidable upon said pin, spring means normally urging the weight member in an upward direction, operative connections between the weight member and said sliding jaw members whereby to normally urge the jaw members in an upward direction, and a cylindrical cup detachably associated with the lower end of said extension for inclosing said weight member and its associated elements.

6. In a well casing pulling device of the character described, a body stock adapted to be attached at its upper end to the raising and lowering rod or cable, an inverted conical shaped cylinder depending from the lower end of said body stock, the outer face 90 of said cylinder being formed with longitudinally extending channels, casing gripping jaw members slidably arranged upon the outer face of said cylinder, ribs upon the inner faces of said jaw members for 95 slidable engagement within the channels, a depending supporting member associated with the inner end of said cylinder, a weight slidable upon said supporting member, means normally urging the weight in an 100 upward direction, and operative connections between said weight and sliding jaws.

7. In a well casing pulling device of the class described, a body stock adapted for attachment at one end to an operating rod or cable, said body consisting of a hollow member tapered at its upper end toward the center of the body and provided with a plurality of slip faces having dove-tailed grooves, casing engaging slips slidable on the faces and having dove-tailed keys to engage the grooves, a rod suspended from the top of the body within the hollow portion, a sliding weight on the rod, an adjustable nut on the rod below the weight, a 115 coil spring between the nut and the weight, pins connected to the inner faces of the slips and links between the pins and the weight.

In testimony whereof I affix my signature. 120
FRED F. WELLMAN.
